United States Patent Office.

CHARLES A. BROWN, OF TROY, NEW YORK.

Design No. 3,557, dated June 29, 1869.

DESIGN FOR A PAPER COLLAR.

The Schedule referred to in these Letters Patent and making part of the same.

To all whom it may concern:

Be it known that I, CHARLES A. BROWN, of the city of Troy, in the county of Rensselaer, and State of New York, have invented or produced a new and original Design for the Fronts of Paper Collars, of which the following is a full, clear, and exact description, reference being had to the accompanying drawings, making a part of this specification.

In the said drawing—

A represents the body, or main portion of a paper collar.

A part, *b c e*, of the front of the collar at each end, is cut wider than the rest of the turn-down portion, or fold, and with the lower part thereof curved, as shown in the drawing, from *c* to *e*.

A portion of the surface of the collar is also embossed, or raised up by stamping or otherwise. This embossed surface runs along the edge *b c*, and along the curved edge *c e*, and continues in a curved line to the point *b*.

Along the inner edge of the said embossed, or raised surface *d c b*, is a line of indentations, representing a row of stitching, the whole being so stamped or marked as to imitate a narrow hem, or fold.

My design, when properly executed, presents the appearance of triangular pieces of cloth hemmed at the edges and sewed on the front of a linen collar, substantially as shown in the said drawing.

What I claim as my invention, and desire to secure by Letters Patent, is—

The design for the fronts of paper collars hereinbefore set forth.

In witness whereof, I have hereunto set my hand, this 3d day of June, 1869.

CHAS. A. BROWN.
